US00D924761S

(12) **United States Design Patent** (10) **Patent No.:** **US D924,761 S**
(45) **Date of Patent:** **** Jul. 13, 2021**

(54) **REARVIEW ASSEMBLY**

(71) Applicant: **Gentex Corporation**, Zeeland, MI (US)

(72) Inventors: **Bradley R. Hamlin**, Allendale, MI (US); **Nigel T. Lock**, Holland, MI (US); **John B. Ostreko**, Hudsonville, MI (US)

(73) Assignee: **GENTEX CORPORATION**, Zeeland, MI (US)

(**) Term: **15 Years**

(21) Appl. No.: **29/695,640**

(22) Filed: **Jun. 20, 2019**

Related U.S. Application Data

(63) Continuation of application No. 29/587,993, filed on Dec. 16, 2016, now Pat. No. Des. 854,473.

(51) **LOC (13) Cl.** **12-16**

(52) **U.S. Cl.**

USPC **D12/187**

(58) **Field of Classification Search**

USPC D12/187-189; D6/300, 309

CPC B60R 1/076; G02B 7/182; G02B 5/08; G02B 7/18

See application file for complete search history.

(57) **CLAIM**

We claim the ornamental design for a rearview assembly, as shown and described.

DESCRIPTION

FIG. 1 is a front perspective view of a rearview assembly of the present disclosure;

FIG. 2 is a rear perspective view of the rearview assembly of FIG. 1;

FIG. 3 is a front elevational view of the rearview assembly of FIG. 1;

FIG. 4 is a rear elevational view of the rearview assembly of FIG. 1;

FIG. 5 is a first side elevational view of the rearview assembly of FIG. 1;

FIG. 6 is a second side elevational view of the rearview assembly of FIG. 1;

FIG. 7 is a top plan view of the rearview assembly of FIG. 1; and,

FIG. 8 is a bottom plan view of the rearview assembly of FIG. 1.

Broken lines are environmental only and form no part of the claimed design.

1 Claim, 6 Drawing Sheets
